INVENTOR

William A. Caswell.

UNITED STATES PATENT OFFICE.

WILLIAM A. CASWELL, OF PROVIDENCE, RHODE ISLAND, ASSIGNOR OF
TWO-THIRDS HIS RIGHT TO EDWIN M. WALDRON AND EDWIN V. BOWEN,
OF SAME PLACE.

IMPROVEMENT IN HOSE-COUPINGS.

Specification forming part of Letters Patent No. **149,441**, dated April 7, 1874; application filed
February 18, 1874.

To all whom it may concern:

Be it known that I, WILLIAM A. CASWELL, of the city and county of Providence, and State of Rhode Island, have invented a new and useful Improvement in Hose-Couplings; and I do hereby declare the following specification, given in connection with drawings furnished, to be a true and exact description thereof.

My invention relates to the swivel and tail-piece of a hose-coupling; and consists in casting one inside the other in such a manner as to connect the two parts, and allow one to revolve upon the other without the possibility of being pulled apart while in service.

Figure 1 represents a hose-coupling, with my improvement drafted in sections, and lettered to correspond with those in specification.

Letter A represents the swivel part of a hose-coupling, with a screw-thread upon its inner surface, extending half its length, and terminating at a recess in the large end; also, a lip or ring at the extreme large end, inside and outside, with a concave band and horns, which I do not claim, except in combination. Letter B represents the tail-piece, with round spiral grooves upon its outer surface, and a flange, E, against which the swivel turns, and against which the band swings up in connecting the tail and band together. Letter C represents the ring or lip at the extreme end of swivel A. Letter H represents the ring or lip at extreme large end of tail B. Thus it will be seen that the two parts are held firmly in position by the interlocked collars. Letter D represents the collar or ring on the lower side of flange E, on which are cut spiral grooves to match the one on tail-piece, and, also, in the band. Letter h represents the band, having round spiral grooves upon its inner surface the whole length, to match one on tail B and collar D. As the band is screwed down

over the outside of the hose, it catches into those on the collar D, connecting the two parts together firmly.

I do not claim the round spiral grooves as my invention, except in combination.

In attaching couplings to rubber hose, whenever any part of the metal pieces has to revolve upon the rubber a great amount of friction is created. To entirely overcome this I insert a piece of strong paper under the band as an anti-friction substance. (Reference to A.)

An explanation of the process by which I connect the swivel and tail-piece of a hose-coupling together by pouring the metal, while in a liquid state, into a cast swivel, will enable all to understand.

I first cast the swivel and finish it, then cut the recess which forms the lip at the extreme end; then I wash these parts in clay-paste, and thoroughly dry out all dampness. I then prepare a sand core, and slip the swivel down over it, and against a shoulder provided to receive it near one end. The whole is then placed in the mold, and the liquid metal poured in, finding its way into recess in the swivel, and around the core, forming the tail-piece. As the metal cools it shrinks sufficient to leave one loose within the other, and allow it to revolve easily.

Having described my invention, I claim as new, and desire to secure by Letters Patent—

1. The swivel A and tail-piece B of a hose-coupling, connected by casting one part to the other, as specified.

2. In combination with the tail-piece B, collar D, and flange E, the interlocking flanges C and H, as and for the purpose specified.

WILLIAM A. CASWELL.

In presence of—

HENRY MARTIN,
JOHN C. PURKIS.
